UNITED STATES PATENT OFFICE.

DON E. BEATLEY AND PETER MAX FELTWELL, OF SEWICKLEY, PENNSYLVANIA.

ELECTRICAL SIGNALING APPARATUS.

1,143,024.

Specification of Letters Patent. Patented June 15, 1915.

Application filed November 13, 1914. Serial No. 871,856.

To all whom it may concern:

Be it known that we, DON E. BEATLEY and PETER MAX FELTWELL, residing at Sewickley, in the county of Allegheny and State of Pennsylvania, citizens of the United States, have invented or discovered certain new and useful Improvements in Electrical Signaling Apparatus, of which improvement the following is a specification.

10 Our invention relates to electrically operated signaling apparatus, and while its application is not limited to any specific purpose, it is particularly well adapted to be used on automobiles, trucks, and like vehicles to notify pedestrians and the drivers of other machines the direction in which it is desired to steer the signal-provided machine.

15 The object of our invention is to improve the general construction and operation of such apparatus, and to provide a construction wherein electrical energy is required only for the purpose of moving a pointing signal and not for maintaining it in one or another desired position.

20 25 A further object of our invention is to provide a construction having the operating feature just described, and wherein an electric lamp circuit may be closed by the signal operating mechanism; and be kept closed as long as the pointing signal is at one position and after the breaking of the circuit used for operating such signal.

30 35 In the accompanying sheet of drawings, which forms part of our specification, we have illustrated one embodiment of our invention.

Figure 1 is a plan view of the signaling apparatus; Fig. 2 a combined elevation and sectional view, the plane of view being indicated by the broken line II-II, Fig. 1; Fig. 3 a diagrammatic representation of the electrical wiring and of the essential elements of the construction shown in Figs. 1 and 2; and Figs. 4 and 5 are views to enlarged scale of a detail of construction.

In the several figures like numerals are used to designate like parts.

45 In the practice of our invention, as illustrated herein, we provide a plurality of 50 electro-magnets, each adapted to be separately energized, and arranged in such positions that a movable magnetic member, lying in the fields of magnetization of all the magnets, may be attracted to a position proximate to which ever magnet may be energized.

A pointing signal is operated by the movable member, the arrangement being such that, when such member is in a position proximate to one or another of the magnets, the signal will be pointing in a desired direction. The magnetic attractive forces are used only for moving the signal, a suitable catch being provided to hold the signal in one or another of the desired positions after the signal-operating magnet has been effective to bring it to such position. However, the catch is such that it may be released, or its effect overcome, when another of the magnets is energized to move the signal to another position. The apparatus also includes means for closing a circuit through one or another of a plurality of electric signaling lamps depending upon the position of the pointing signal, and for this purpose means are provided to maintain a closed circuit through a lamp as long as the signal points in a given direction and after the magnet-energizing circuit has been opened.

Referring now to the embodiment of the invention illustrated in the drawings, three 80 electro-magnets 1, 1^a and 1^b are mounted radially upon a suitable block 2, and the movable member 3, 4 is pivoted upon a support 5, the arm 3 lying in the fields of magnetization of all the magnets. The outer 85 end of the arm 4 is provided with teeth which mesh with a pinion 6 secured to a shaft 7 which carries the pointing signal or arrow 8. The catch for holding the member 3, 4 in positions proximate to any of the 90 magnets may be of any desired construction, that shown herein (seen best in Figs. 4 and 5) consisting of a ball 9 held yieldingly against the lower face of the arm 4 by means of a spring 10, and adapted to enter 95 one or another of the depressions 11, 11^a and 11^b, depending upon whether the arm 3 is nearest to the magnets 1, 1^a and 1^b, respectively. The catch is of sufficient strength to hold the member 3, 4, and hence the pointer 100 8, in one position or another after such member has been moved by the attractive force of an energized magnet, but insufficient for this purpose when another magnet has been energized.

To separately energize each of the magnets, the wiring and the operating switch may be such as is illustrated in Fig. 3. As shown therein, the coil of each magnet is connected to a common conductor 12, which

is connected by a conductor 13 to one side of a battery 14, the other side of which is connected by a conductor 15 to a conducting element 16, having three spring arms 17, 17^a and 17^b. The element 16 is mounted on an insulation block 18, to which there are also secured contactors 19, 19^a and 19^b, such contactors being beneath the arms 17, 17^a and 17^b respectively. These arms are normally out of contact with the contactors, but may be put in contact therewith by pressing buttons 20, 20^a and 20^b, suitably mounted in a casing 21, as seen in Figs. 1 and 2. Extending from, and electrically connected to, the contactors 19, 19^a and 19^b there are conductors 22, 22^a and 22^b, which are electrically connected to the several magnets 1, 1^a and 1^b, respectively. By this arrangement it will be seen that, when one of the buttons has been pressed, a circuit will be closed through the battery and one of the electro-magnets; for example, by pressing the button 20, the arm 17 will be brought into contact with the contactor 19, so that a circuit will be closed through the arm 17, contacts 19, conductor 22, electro-magnet 1, conductors 23, 12, 13, battery 14, conductor 15 and conducting element 16, the result being that the arm 3 will be moved from its position proximate to either of the magnets 1^a or 1^b to a position proximate to the magnet 1, and the pointer 8 will consequently assume the position indicated in full lines in the drawings.

In the illustrative embodiment of our invention two signal lamps 23^a and 23^b are shown mounted on the block 2 at opposite sides of the pointer 8. The globes of these lamps may be of different colors, as for example red and green, and means are provided to close a circuit through one or the other of the lamps when the pointer is moved to the right or left of the position indicated in full lines. For this purpose both lamps are connected on one side to a common conductor 24, and on their other sides to conductors 25^a and 25^b, which in turn are electrically connected respectively to contact posts 26^a and 26^b, against which posts the arm 4 bears when the arm 3 is in a position proximate to the magnets 1^a and 1^b, respectively. The member 3, 4 is of conducting material, as well as the post 5 on which it is pivoted. A conductor 27 is electrically connected to the post 5 and to the conductor 12, and a conductor 28 connects the conductor 24 to a contactor 29, mounted in the switch casing. A spring arm 30 of conducting material is adapted to be held, by means of a slide button 31, in continuous engagement with the contactor 29, the circuit being then completed by a conductor 32 between the arm 30 and the conductor 15.

In the operation of the apparatus shown herein, when the slide 31 is moved to the

position opposite to that indicated in Fig. 1, the spring arm 30 will be out of contact with the contactor 29, so that the lamps 23^a and 23^b will not be lighted according to the position of the pointer. This is the arrangement of circuits intended for daylight use for automobiles. The movable parts being in the positions shown in the drawings, pressing the button 20^a will close a circuit through the magnet 1^a with the result that the arm 3 will be moved to a position near the magnet 1^a and the pointer 8 moved to the position indicated by dotted lines in Fig. 1. The circuit thus closed will be through conductor 22^a, magnet 1^a, conductors 12 and 13, battery 14, conductor 15, conducting element 16, arm 17^a and contactor 19^a. As soon as the arm 3 has been moved the circuit may again be opened by removing pressure upon the button 20^a, and the arm 3, 4 will be held in its new position by means of the yielding catch, the ball 9 being then in the recess 11^a. When it is desired to return the pointer to its normal position, as indicated in full lines, the button 20 may be pressed to close the circuit through the magnet 1, the attractive force of which will overcome the tendency of the catch to hold the arm 3 in its position near the magnet 1^a. In a similar way the arm 3 may be moved toward the magnet 1^b by pressing the button 20^b, and it will be understood that the arm may be moved to this last mentioned position from positions proximate to either the magnet 1 or 1^a.

At night time, when it is desirable to indicate directions by both the pointer and the lamps, the button 31 is pushed to the position indicated in Fig. 1, thereby pressing the arm 30 in contact with the contactor 29. The movement of the arm 3 toward the magnet 1^a, and the pointer 8 to the dotted line position indicated in Fig. 1, may then be effected by pressing the button 20^a, the operation being the same as explained in the above paragraph. When the member 3, 4 has been thus moved, the arm 4 thereof will be in electrical contact with the contact post 26^a, so that a circuit will be closed through the lamp 23^a and the battery 14. This circuit will be through conductors 28 and 24, lamp 23^a, conductor 25^a, contact post 26^a, arm 4 of the member 3, 4, support 5, conductors 27, 12 and 13, battery 14, conductors 15 and 32, arm 30 and contactor 29. Such circuit will remain closed as long as the arm 4 is in contact with the post 26^a, and after the circuit has been opened through the magnet 1^a. In a similar manner the lamp 23^b may be lighted and kept burning when the magnet 1^b is energized.

When the apparatus which we have described is used on an automobile, it may be placed in any suitable position, preferably on the front of the car, and, when desirable, a similar apparatus may be placed at the

rear by a mere duplication of parts and wiring, as will be readily understood by those skilled in the art.

We claim as our invention:

- 5 In a signaling apparatus, the combination of three radially arranged electromagnets, an electric switch in circuit therewith and adapted to make and break an electric circuit through one or another of said magnets,
- 10 a horizontally-disposed pivotally-mounted arm having one end thereof in the field of magnetization of each of said magnets, the other end of said arm being provided with ratchet teeth, a vertically disposed rod pro-
- 15 vided with a pinion meshing with said teeth and having an indicating arm secured to its outer end, a pair of signal lamps, means

for placing said lamps in circuit with said magnets, a contactor in circuit with each of said lamps, each contactor being adapted 20 to be engaged by said arm and when thus engaged to close a circuit through a lamp, and a catch for holding said arm in contact with one or the other of said contactors after the circuit through a magnet has been 25 broken.

In testimony whereof we have hereunto set our hands.

DON E. BEATLEY.
PETER MAX FELTWELL.
